UNITED STATES PATENT OFFICE.

CHARLES E. KILBOURNE, OF WORCESTER, MASSACHUSETTS, ASSIGNOR TO HARDER
REFRIGERATOR CORPORATION, A CORPORATION OF NEW YORK.

REFRIGERATOR-DRAIN TRAP.

Application filed October 4, 1927. Serial No. 223,939.

My invention has particular reference to traps for domestic refrigerators the principal function of which is to make an air-tight water seal and thus prevent warm air from 5 the outside of the refrigerator from entering into the ice chamber while the refrigerator is closed and also prevent odors from entering through the waste pipe. Traps of this sort are commonly located within the refrigerator and are inserted at a convenient 10 place in the drain pipe communicating with the ice chamber.

One of the advantages of my trap is the fact that it may be stamped from sheet 15 metal. It is composed of three parts, a bowl member communicating with the external drain pipe, a baffle, and a cover telescoping with the bowl member and connected to the drain pipe from the ice chamber. Not only 20 is my trap easy to manufacture, assemble and install, but it is unusually strong and durable and it provides an effective seal under all ordinary conditions. In fact its sealing 25 effectiveness is not impaired by a considerable departure from a level situation for the refrigerator. Another advantage of the construction afforded in my invention is the fact that it cannot be incorrectly assembled. Still other objects and advantages of my invention 30 will appear from the following particular description of one embodiment of my invention as illustrated in the accompanying drawings in which:

Fig. 1 is a sectional elevation of a portion 35 of a refrigerator with a trap embodying my invention incorporated therein;

Fig. 2 is a sectional elevation through the trap and adjacent parts, and

Fig. 3 is a plan of the trap with the cover 40 removed.

In Fig. 1 the trap as a whole is indicated by the reference character A. It is inserted in the drain pipe B which commonly extends down along the rear wall of the compartment C of the ice box D and connects 45 at its upper end with the nipple E of the drain outlet from the ice chamber F. From the bottom of the trap A leads the outlet drain pipe G which extends through the 50 bottom of the refrigerator and leads to a suitable waste drain.

Referring to Fig. 2, the bowl member of the trap is numbered 1, the baffle is numbered 2 and the cover is numbered 3. As shown the 55 trap is stamped entirely from suitable sheet

metal such as copper or zinc. The side walls of the bowl member are cylindrical and near the top it is provided with a circumferential bead 4 which serves both to strengthen the wall and also as a stop for the cylindrical 60 portion of the cover which is shown as telescoping within the bowl member.

The bottom of the bowl member is provided with a central overflow orifice 5 which is raised above the bottom of the bowl, the 65 wall being then continued into a coupling sleeve 6 which telescopes over the bottom section G of the drain tube.

The bottom of the bowl about the raised overflow orifice constitutes a water pocket 7 70 and in cross section this water pocket is substantially semicircular, merging with the cylindrical wall portion of the bowl on substantially the plane of the overflow orifice. Thus the water pocket is made of substantial 75 capacity and at the same time it is altogether sanitary and easily cleaned.

The baffle 2 is dome shape, being substantially hemispherical, and has a knob 8 formed in its top to enable it to be easily 80 grasped with the fingers. It is disposed centrally over the outlet orifice of the bowl and is of a size to stand in the bottom of the water pocket 7. In order to provide a vent or vents for the water, sections of the lower 85 edge are cut away leaving a plurality of feet 9 (shown as four in number). The height of the feet is such that the lower edge of the baffle is below the level of the outlet orifice 5 and is, therefore, immersed in the water of 90 the water pocket.

It is desirable that even in a tilted position of the refrigerator, the baffle remain substantially central and be prevented from sliding over against the walls of the outlet orifice 95 and thus restrict the flow of water from the pocket to the orifice. It is also desirable that the bottom edge of the baffle be immersed in the water even in a considerably tilted position of the refrigerator. These desirable 100 results are attained by my construction. Due to the curved shape of the bottom of the water pocket and the proportion of the baffle which causes its bottom edge to be disposed over the deepest part of the pocket, the baffle tends to stay in its central position and its bottom edge is comparatively deeply immersed in the water. The baffle is further restrained from any tendency to slide out of 105 its proper relative position due to an incli- 110

nation of the drain pipe, by reason of the fact that the feet are inclined outwardly so as to bear against the wall of the water pocket where it curves upwardly from the deepest part toward the cylindrical side walls. In the illustrated construction this outward inclination of the feet is effected by crimping each foot vertically so as to form a central outstanding rib 10, which bears well up along the outer part of the curved wall of the water pocket. These ribs also serve to strengthen the feet. The bottom faces of the ribs are beveled off, as shown, so as to conform substantially to the curvature of the wall of the water pocket.

The cover 3 completes the device. It is generally dome shape, terminating at its bottom in a cylindrical portion which telescopes within the bowl member. Alternatively, of course, the bead 4 in the side wall of the bowl member may be outwardly turned and the cover of the bowl may be so proportioned in diameter that the cover telescopes over the top of the bowl.

The cover has a central inlet orifice and is continued upwardly into a short neck or sleeve portion 11 which telescopes over the drain pipe B and thus couples the trap to the drain pipe. At the bottom of the neck or sleeve the diameter is slightly restricted by the formation of an inwardly turned bead 12 which serves to limit the telescopic engagement of the cover on the drain pipe.

One of the features of my trap is the fact that the inlet coupling sleeve 11 and the outlet coupling sleeve 6 are of different diameters. This makes it impossible to reverse the

positions of the bowl and cover. This difference in size of the two coupling sleeves may be accommodated in making the connections either by making the two drain pipe sections B and G of different diameters or by telescoping one of the coupling sleeves over its drain pipe section and telescoping the other coupling sleeve into its drain pipe section.

It is obvious that various modifications may be made in the construction shown in the drawings and above particularly described within the principle and scope of my invention.

I claim:

A refrigerator trap comprising a bowl member having a raised central overflow orifice and a coupling sleeve integrally joined to the bowl member at the overflow orifice, the annular water pocket thus provided in the bottom of the bowl being substantially semicircular in cross section, and a substantially hemispherical baffle loosely arranged over the overflow orifice and having its bottom edge discontinuous thereby providing spaced feet, the diameter of the bottom of the baffle being substantially that of the deepest part of the water pocket and the feet having each a central vertical rib the bottom of which is shaped substantially to the curve of the water pocket so as to bear against an upwardly curving portion of the water pocket wall and allow the feet to rest in the bottom of the pocket.

In witness whereof, I hereunto subscribe my signature.

CHARLES E. KILBOURNE.
